UNITED STATES PATENT OFFICE.

EWALD HÄHNEL, OF HOBOKEN, N. J., ASSIGNOR TO PALM & FECHTELER,
OF NEW YORK, N. Y.

DESIGN FOR ORNAMENTATION OF SEWING-MACHINES.

SPECIFICATION forming part of Design No. 12,306, dated June 14, 1881.

Application filed April 25, 1881. Term of patent 7 years.

To all whom it may concern:

Be it known that I, EWALD HÄHNEL, of the city of Hoboken, county of Hudson, and State of New Jersey, have invented a new and original Design for the Ornamentation of Sewing-Machines, of which the following is a specification.

This invention relates to a new and original design for the ornamentation of sewing-machines and other articles; and it consists in the novel grouping and configuration of figures, hereinafter more fully described.

The accompanying illustrations show, in Figures 1 and 2, opposite views of a sewing-machine plate and arm having thereon my new design. Fig. 3 is a side view of the sewing-machine arm; Fig. 4, a face view of the ornament at the end of said arm; Fig. 5, a top view of the cloth-plate ornamented according to this invention.

The figure A is a curving vine bearing upon it rose-like flowers and buds and leaves, the flowers being found within the spirals of the curving vine and the leaves growing upon slender stems projecting from the spirals. This figure A is L-shaped and extends along the sides of the rectangular arm of the sewing-machine plate.

The figure B is a vine whose spirals circle around a central rose-like figure and project on each side of it. This vine bears rose-leaves, and has a rosebud contained within each of its end spirals, the buds projecting in opposite directions. The ornaments B are placed against the sides of the needle-carrying arm.

The figure C is a vine circling around a central rose-like figure, and bearing upon it leaves and tendrils arranged as shown. This figure is applied to the face of the needle-carrying bar.

The figure D is also a vine curving in spirals around a central rose-like figure and extending on each side of it, and bearing rose-bush-like leaves. It is placed on the front end of the cloth-plate.

The figure E, which is placed along one side of the cloth-plate, is a spirally-curving vine, bearing upon it leaves and tendrils, and having rose-like flowers and one bud within its spirals.

The figure G, placed along the opposite side

of the cloth-plate, is also a spirally-curving vine, having rose-like flowers within some of the curves and bearing leaves and tendrils.

The figure H, which is interposed between figures D and E, is made of two vines, each having in its center a rose-like flower, and leaves and tendrils at its ends. The two vines of the figures H stand in opposite curves, as shown.

The figure I, between figures D and G, is like the figure H. These figures D E G H I are found around the sewing-plate in the photograph.

I do not broadly claim a design involving vines, roses, and leaves with or without buds; but

I claim—

1. The design for the ornamentation of sewing-machines, consisting of the L-shaped figure A, substantially as shown. 70

2. The design for the ornamentation of sewing-machines, consisting of the figure B, substantially as shown.

3. The design for the ornamentation of sewing-machines, consisting of the figure C, substantially as shown. 75

4. The design for the ornamentation of sewing-machines, consisting of the figure D, substantially as shown.

5. The design for the ornamentation of sewing-machines, consisting of the figure E, substantially as shown. 80

6. The design for the ornamentation of sewing-machines, consisting of the figure G, substantially as shown. 85

7. The design for the ornamentation of sewing-machines, consisting of the figure H, substantially as shown.

8. The design for the ornamentation of sewing-machines, consisting of the figures E H D I 90 G, substantially as shown.

9. The design for the ornamentation of sewing-machines, consisting of the figures A and B, substantially as shown.

10. The design for the ornamentation of sewing-machines, consisting of the figures A B C D E G H I, substantially as shown. 95

EWALD HÄHNEL.
